UNITED STATES PATENT OFFICE.

SELLMAR M. JACOBY, OF NEW YORK, N. Y.

SEWING-MACHINE.

SPECIFICATION forming part of Letters Patent No. 643,326, dated February 13, 1900.

Application filed May 8, 1899. Serial No. 716,041. (No model.)

To all whom it may concern:

Be it known that I, SELLMAR M. JACOBY, a citizen of the United States, and a resident of New York, in the county and State of New York, have invented a new and useful Improvement in Sewing-Machines, of which the following is a specification.

My invention relates to an improvement in sewing-machines, and more particularly to the feed mechanism thereof.

The object of my invention is to provide a feed mechanism which will run very smoothly and easily, thereby reducing the wear and tear of the machine to a minimum and also enabling the machine to be run at a very high rate of speed.

A practical embodiment of my invention is represented in the accompanying drawings, in which—

Figure 1 represents a front view of a portion of a sewing-machine with my improved feed mechanism applied thereto. Fig. 2 is an end view of the same, with the feed mechanism represented in position No. 1. Fig. 3 is a rear view of the same. Fig. 4 is a top plan view partially in section. Fig. 5 represents an end view with the feed mechanism in position No. 2. Fig. 6 represents an end view with the feed mechanism in position No. 3, and Fig. 7 is an end view with the feed mechanism in position No. 4.

In the drawings I have represented the feed mechanism in four positions assumed at the beginning of each quadrant of angular motion of the feed-actuating shaft during one revolution of the said shaft, and I have at the same time also shown the proper position of the needle at the same periods.

The base of the sewing-machine is denoted by A, and it is surmounted, as is usual, by a table a.

The foot is denoted by B and the needle by b, and they may be operated in the usual manner in conjunction with the feed mechanism.

The rotary feed-actuating shaft is denoted by C, and it is mounted in the base A of the frame, as is usual. The outer end of the feed-actuating shaft C is provided with an eccentric c for imparting to the feeding mechanism its forward and backward reciprocating movements and with a second eccentric c' for imparting to the feed mechanism its re-

ciprocating upward and downward movements. These eccentrics are arranged in the proper relation to the center of the shaft C 55 so as to impart the several movements to the feed mechanisms at the proper periods during the revolution of the shaft.

The feed-bar is denoted by D, and it is provided with a feed-dog d, secured thereto in 60 vertical adjustment by means of a set-screw d'. This feed-bar D is hinged at its rear end, as shown at d², to the free end of a rocking arm E, which is hinged at e to the outer face a' of the base A. The forward end of the 65 feed-bar D is bifurcated to receive therein the eccentric c' for imparting to the feed-bar its reciprocating upward and downward movements.

The device which I employ for imparting to the feed-bar its reciprocating forward and backward movements comprises a toggle-lever having one of its arms F connected with the rocking arm E and its other arm adjustably secured to the end face a' of the base A, 75 which toggle-lever is connected at the junction of its arms with an eccentric-arm F², the strap of which embraces the eccentric c upon the rotary feed-actuating shaft C. The rear end of the arm F of the toggle-lever is secured at f to the said rocking arm E at a point between its hinged connection with the end face of the base A and its connection with the feed-bar D. The forward end of the arm F' of the toggle-lever is provided with a screw 80 f', which passes through a curved elongated slot a² in the face of the base A, which screw is provided with a clamping thumb-nut f² upon the opposite side of the face from the arm F', so that the outer end of the said arm 85 may be adjustably secured in different positions nearer to or farther from the hinged end of the rocking arm E. The screw f' is preferably provided with a sleeve f³, fitted to travel within the slot a² for guiding the 90 screw when it is being adjusted.

By the above arrangement the length of the feed may be readily increased or decreased by adjusting the free end of the arm F' of the toggle-lever toward and away from the hinged 100 end of the rocking arm E.

By the structure hereinabove set forth I am enabled to provide a feed mechanism for sewing-machines which will run very smoothly

and with very slight wear and tear and also provide a mechanism in which the several parts are so located that access may be readily obtained to them for purposes of adjustment or replacement.

What I claim is—

1. A feed mechanism for sewing-machines comprising a suitable support, a rotary actuating-shaft having two eccentrics thereon, a 10 rocking arm hinged to said support, a feed-bar hinged to said arm and engaged with one of the said eccentrics, a toggle-lever having one of its arms hinged to the support and its other arm hinged to the said rocking arm, 15 and an eccentric-arm embracing the other eccentric on the rotary actuating-shaft and connected with the toggle-lever at the junction of its arms, substantially as set forth.
2. A feed mechanism for sewing-machines 20 comprising a suitable support, a rotary actuating-shaft having two eccentrics thereon, a

rocking arm hinged to said support, a feed-bar hinged to said rocking arm and engaged with one of the said eccentrics, a toggle-lever having one of its arms hinged to the said rocking 25 arm and its other arm hinged to the support, an eccentric-arm embracing the other eccentric on the rotary actuating-shaft and connected at the junction of the arms of the toggle-lever and means for securing the hinged 30 end of the arm of the toggle-lever which is connected with the support in different positions on the support, substantially as set forth.

In testimony that I claim the foregoing as 35 my invention I have signed my name, in presence of two witnesses, this 5th day of May, 1899.

SELLMAR M. JACOBY.
